QUICK-CHANGE GUN SIGHT

Wilbert E. Olson, St. Paul, Minn.

Application June 16, 1948, Serial No. 33,279

3 Claims. (Cl. 33—47)

1

This invention relates to gun sights.

It is an object of the present invention to provide a gun sight which can replace one sight upon the gun for another sight so that a sight employing a lens which may have become wet or inoperative can be quickly replaced with a sight not employing the lens and operable in all kinds of weather.

Other objects of the present invention are to provide a quick change gun sight which is of simple construction, easy to apply upon the gun, inexpensive to manufacture and efficient in operation.

For other objects and for a better understanding of the invention, reference may be had to the following detailed description taken in connection with the accompanying drawing, in which

Fig. 1 is a perspective view of a gun with the sight embodying the features of the present invention connected thereto.

Fig. 2 is a top plan view of the sight.

Fig. 3 is a side elevational view of the sight.

Fig. 4 is an end elevational view of the sight.

Fig. 5 is a bottom plan view of the sight.

Referring now to the figures, 10 represents a gun having a barrel 11 on the rear end of which there may be mounted a gun sight 12 embodying the features of the present invention. A gun stock is connected to the rear end of the barrel as indicated at 13. On the forward end of the barrel there can be releasably connected a front sight 14. The rear of the barrel, as shown in Fig. 3, has screws 15 and 16 protruding upwardly from the top thereof and centering posts 18 and 19. Adapted to be fitted over these posts and screws is a main sighting piece 21 having a sighting groove 22 in the top of the same. The bottom face of the piece 21 has large openings 22' to receive the screws 15 and 16 and small openings 23 to receive the centering pins 18 and 19. The bottom face of the sighting piece is grooved to fit the top surface of the barrel and in flush engagement therewith.

Adapted to be threaded into the top of the barrel in a threaded opening 25 is a screw 26 having a large flat head 27. With the screw extended to a raised position, the piece 21 can be extended over the head, there being a slot 28 extending through the sides of the piece and a narrow slot extending from one bottom edge of the piece to accommodate the screw shank 26. This narrow slot is indicated at 29. The groove 22 is knurled as indicated at 31.

By a simple operation, the sighting piece 21

2

can be placed upon the top of the barrel or removed therefrom. The screw 26 may remain in place and be adapted to receive other sighting pieces.

While various changes may be made in the detail construction, it shall be understood that such changes shall be within the spirit and scope of the present invention as defined by the appended claims.

10 I claim:

1. A sighting piece adapted to be connected to a gun barrel comprising a grooved bottom face adapted to fit the top of the gun barrel, a transverse slot elevated from the bottom face and extending from one side of the piece to the other, a screw adapted to be fitted into the top of the barrel and having a head adapted to enter the transverse slot and extend from the opposite sides of the piece whereby the screw can be turned from the opposite sides thereof, and said piece having a narrow slot extending from one side of the piece for receiving the screw shank.

2. A sighting piece adapted to be connected to a gun barrel comprising a grooved bottom face adapted to fit the top of the gun barrel, a transverse slot elevated from the bottom face and extending from one side of the piece to the other, a screw adapted to be fitted into the top of the barrel and having a head adapted to enter the transverse slot and extend from the opposite sides of the piece whereby the screw can be turned from the opposite sides thereof, and said piece having a narrow slot extending from one side of the piece for receiving the screw shank, and said 35 sighting piece having a top groove with a knurled bottom face.

3. A sighting piece adapted to be connected to a gun barrel comprising a grooved bottom face adapted to fit the top of the gun barrel, a transverse slot elevated from the bottom face and extending from one side of the piece to the other, a screw adapted to be fitted into the top of the barrel and having a head adapted to enter the transverse slot and extend from the opposite sides 45 of the piece whereby the screw can be turned from the opposite sides thereof, and said piece having a narrow slot extending from one side of the piece for receiving the screw shank, and said bottom groove having depressions therein adapted to receive projections from the top face of the barrel.

WILBERT E. OLSON.
